UNITED STATES PATENT OFFICE.

PAUL VUILLAUME, OF MARSEILLE, FRANCE.

REFRIGERATING APPARATUS.

Application filed June 16, 1924, Serial No. 720,294, and in France June 3, 1924.

This invention relates, more particularly, to portable refrigerating apparatus of the absorption type.

Apparatus, heretofore proposed, usually comprise generator adapted for convenient heating of its contents, means such as a thermometer or other devices for ascertaining the temperature within the chamber, a stoppered or valve-controlled pipe for introducing liquid refrigerant to the generator, a long valve controlled conduit to convey gas to an evaporator and a valve to control the return of gas or fluid to the generator.

The object of my invention is to provide a refrigerating apparatus which, by reason of its peculiar construction, will possess certain advantages as, for instance, quicker heating of the liquid refrigerant, a smaller and, consequently, more portable generator due to the large internal capacity of the gas conduit, efficiency due to the particular arrangement and construction of component parts, and means for insuring safety from danger entailed by excessive pressure within the apparatus.

With the above objects in view, my invention consists in the construction, arrangement and combination of parts as herein-after described and set forth in the appended claims.

Reference being had to the drawings for a more concise description of my invention:

Figure 1, shows, in vertical section, a refrigerating apparatus constructed in accordance with my invention; Fig. 2, is a vertical section of the valve casing drawn to a large scale; Fig. 3, is a vertical section illustrating a slight modification of the mechanism shown in Fig. 2; Fig. 4 is a vertical section of an alternative form of refrigerating chamber, the section being taken on the line *a'-b'* of Fig. 5; Fig. 5 is a plan of the refrigerating chamber shown in Fig. 4.

The hollow cylindrical generator 1 has end closures 2, 3. A series of tubes 4 connect the closure 2 with the wall of the generator 1 and serve to convey hot gas, from the source of heat, through the liquid within the chamber, thereby greatly increasing the heating surface and expediting the conversion of the liquid into gas. I am aware that such tubes have been employed in boilers and the like, and I therefore do not claim their use broad-

ly as my invention, but only in combination with refrigerating apparatus of the type to which my invention appertains. The chamber 1 has the customarily employed heat indicator consisting as shown in the present instance, of an inwardly projecting tube 9 containing a stem of fusible material surrounded by a weight 10. The weight may be provided with any suitable means, such as a projection 10^a for operating electric contacts or other means which will result in the extinction of the flame, beneath the generator when the temperature is such as to cause the weight to fall.

A gas conduit 5, which in such apparatus has heretofore been made of considerable length to provide considerable surface exposed to the air and thereby to ensure condensation in the inner surface and falling back into the generator of liquid, thus permitting only substantially dry gas to enter the refrigerating chamber, is, in this construction, of considerable diameter in order to provide the required large surface for such condensation, besides providing a large internal capacity thereby enabling a generator of smaller and more portable size to be used and, simultaneously providing a large internal straight and unobstructed passage through which the gas flows freely to the refrigerating chambers. The conduit is however preferably inclined to enhance the tendency of moisture to collect upon its inner surface.

A casing 6, situated at the upper end of the conduit 5 has, in its lower part, a series of openings 13, of which the upper ends constitute seats for ball valves 13^a, there being also a centrally disposed opening 11. This opening is normally closed by a valve 12 within the space 14 enclosed by a flexible diaphragm 15 of which the edge of a central opening therein is clamped between a shoulder 38 and a ferrule 39 screw-threaded onto the upper part of the valve. A cap 40 is secured to the upper end of the casing 6 and is retained in place by a collar 41 which has external screw-threads to engage corresponding internal threads respectively in the upper part of the casing 6 and the cap 40. The under surface of the collar 41 is dished, as at 42 to permit the diaphragm 15 to flex when the valve 12 is raised or lowered. A recess 43 in the collar 41 constitutes, with the cap 40, an annular groove to receive a flange 44,

of a tubular stem 45 to which is secured, by screw-threads or the like a knob 16 (Fig. 2). The stem 45 has threads 46 to engage threads 47 on the ferrule 39 so that when the knob 16 is turned the engaging threads will raise or lower the valve 12 from or onto its seat.

Means for inserting liquid into the generator comprise a tubular nipple 33, screwed tightly into the ferrule 39 and having 10 tightly screwed or otherwise secured thereon a cap which may constitute a gland or knob 36, through which passes a stem 30 having a bore 31 terminating in an off-set opening 32. The lower end of the stem 30 is tapered to 15 normally close a perforation 48 in the lower end of the nipple 33. By means of the knob 36 the nipple 33 can be prevented from turning whilst the stem 30 is turned to raise or lower it. This perforation 48 coincides with 20 a passage 49 in the valve 12, the opening 11, and a pipe 7 extending downwardly into and near to the bottom of the generator.

In Fig. 3 a simplified construction is shown, whereby the valve 12, diaphragm 15, 25 collar 41, tubular stem 45, knob 16 and cap 40, are dispensed with, the last being substituted by a plug 50 into which the nipple 33 is received; its shape being slightly modified and its lower extremity furnished with 30 a ring 51 to prevent displacement of the balls 13^a from the space 14 when, as herein-after described, the apparatus is inclined.

A tube 18 connects the interior 14 of the 35 casing 6 with the interior of the refrigerating chamber 8. The chamber has a centrally disposed opening 17 to receive a container 24 for substances or liquids to be cooled or frozen. It will be understood, however, that a suitably formed refrigerating chamber 40 may be inserted into a vessel containing the substance or liquid to be cooled or frozen.

An alternative construction of the refrigerating chamber (Fig. 4) comprises an enlarged upper part 25 from the bottom 27 of 45 which depend three receptacles 28 each having an outer wall 26 to constitute an intervening space for gas. The pipe 18 may enter the opening 29. The refrigerating chambers are immersed in a tank 23 containing water.

A tube 19, projecting from the conduit 5 has attached to it, by screw-threads, a casing 19^a of which the other end is attached to a pipe 22 having its lower end immersed in 55 the water within the tank 23. The casing contains a valve 20 adapted, by means of a spring 21, to normally close the opening in the pipe 19.

The operation of the apparatus is as follows:—

The valve stem 30 having been raised from its seat 48, suitable freezing liquid can be injected through the bore 31 and passages in the adjacent parts to and through the 65 pipe 7 until the level of the liquid is approx-

imately that indicated by the letter N. The valve stem is then readjusted upon its seat. Inasmuch as the liquid is capable of continuous use refilling will not be of frequent occurrence and therefore to attain neatness the nipple 33 and the valve stem 30 may be cut off at the level indicated by the line a—a in Fig. 3 the knob or gland 36 being also removed. The knob 16 may then be substituted by another knob (Fig. 1) not having an opening to permit the extension through it of the knob or gland 36 shown in Fig. 2, the parts then taking the form shown in Fig. 1. Similarly, the superfluous parts 30, 36, and upper part of the nipple 33 can be removed where indicated by the line b—b in Fig. 3. The thermostat or the like 10 having been arranged in the tube 9, heat is applied to the underside of the generator. Gas then flows past the valves 13^a to the refrigerating chamber 8 from whence it can not return past the valves 13^a and may be retained in the chamber 8 so long as convenient or until required. When the liquid reaches as low level as, for instance, that indicated by the letter N¹, the temperature will be such that the stem which supports the weight 10 will fuse and, the weight falling, the flame constituting the source of heat will be extinguished. In the event of the pressure rising too high, gas will escape past the valve 20 to the water in the receptacle 23 and possible fracture of the apparatus is prevented.

The valve 12 being raised by turning of the knob 16, gas will return and commingle with the fluid in the generator and the reduced temperature in the chamber 8 will be communicated to the contents of the receptacle 24. When the device shown in Fig. 3 is used the gas will return unimpeded to the pipe 7 and generator and freezing will continue so long as the supply of gas lasts. Any fluid in the chamber 8 can be poured back into the generator by raising the chamber 8, the operation being facilitated by the inclination of the pipe 18.

What I claim is:—

1. In a refrigerating apparatus comprising a generator in which a liquid refrigerant can be converted into gaseous refrigerant by the application of heat, an upwardly extending gas conduit of straight tubular formation, and a closed casing surmounting the gas conduit, of which the bottom separates the casing and conduit, a series of annularly disposed openings in said bottom, valves normally closing said openings, a centrally disposed opening in the bottom of the casing, a pipe connecting said opening with the interior of the generator and extending therein to a point which is nearly at the bottom thereof, and a pipe connecting said closed casing with an evaporator.

2. In a refrigerating apparatus comprising

ing a generator in which a liquid refrigerant can be converted into gaseous refrigerant by the application of heat, an upwardly extending gas conduit of straight tubular formation, and a closed casing surmounting the gas conduit, of which the bottom separates the casing and conduit, a series of annularly disposed openings in said bottom, valves normally closing said openings, a centrally disposed opening in the bottom of the casing, a pipe connecting said opening with the interior of the generator and extending therein to a point which is nearly at the bottom thereof, a valve having a centrally disposed aperture surmounting and normally closing the aforesaid centrally disposed opening, a flexible diaphragm situated above said valve, and means for raising and lowering said valve, and an inclined pipe connecting said closed casing with an evaporator.

3. In a refrigerating apparatus comprising a generator in which a liquid refrigerant can be converted into gaseous refrigerant by the application of heat, an upwardly extending gas conduit of straight tubular formation and a closed casing surmounting the gas conduit, of which the bottom separates the casing and conduit, a series of annularly disposed openings in said bottom, valves normally closing said openings, a centrally disposed opening in the bottom of the casing, a pipe connecting said opening with the interior of the generator and extending therein to a point which is nearly at the bottom thereof, a valve having a centrally disposed aperture surmounting and normally closing the aforesaid centrally disposed opening, a flexible diaphragm situated above said valve, means for raising and lowering said valve, said means consisting of a ferrule attached to said valve, a rotatable tubular stem encompassing said ferrule, a knob on said stem, interengaging screw-threads on said ferrule and tubular stem respectively, means for retaining said rotatable tubular stem in place, said means comprising a cap having a central opening, a ring within the cap, said ring extending into the upper part of the aforesaid casing, and being exteriorly screw-threaded to engage threads respectively on the inner surfaces of the cap and casing, an annular recess formed by said ring and cap, in which groove an annular flange on the aforesaid rotatable tubular stem is rotatably retained and an inclined pipe connecting the aforesaid closed casing with an evaporator.

4. In a refrigerating apparatus comprising a generator in which a liquid refrigerant can be converted into gaseous refrigerant by the application of heat, an upwardly extending gas conduit of straight tubular formation, and a closed casing surmounting the gas conduit, of which the bottom separates the casing and conduit, a series of annularly disposed openings in said bottom,

valves normally closing said openings, a centrally disposed opening in the bottom of the casing, a pipe connecting said opening with the interior of the generator and extending therein to a point which is nearly at the bottom thereof, a valve having a centrally disposed aperture, surmounting and normally closing the aforesaid centrally disposed opening, a flexible diaphragm situated above said valve, means for raising and lowering said valve, said means consisting of a ferrule attached to said valve, a rotatable tubular stem encompassing said ferrule, a knob on said stem, interengaging screw-threads on said ferrule and tubular stem respectively, means for permitting injection of fluid into the evaporating chamber, said means comprising a nipple screw-threaded into the aforesaid ferrule, a centrally bored stem screw-threaded into the aforesaid nipple and normally closing an opening in the end thereof said opening being aligned with a centrally disposed opening in the aforesaid valve, a centrally disposed opening in the bottom of the casing and a tube extending into the generator, the aforesaid nipple, centrally bored stem and knob on said nipple being adapted for severance and partial removal for the purpose described, and an inclined pipe connecting the aforesaid closed casing with an evaporator.

5. In a refrigerating apparatus comprising a generator in which a liquid refrigerant can be converted into gaseous refrigerant by the application of heat, an upwardly extending gas conduit of straight tubular formation, and a closed casing surmounting the gas conduit, of which the bottom separates the casing and conduit, a series of annularly disposed openings in said bottom valves normally closing said openings, a centrally disposed opening in the bottom of the casing, a pipe connecting said opening with the interior of the generator and extending therein to a point which is nearly at the bottom thereof, a pipe connecting said closed casing with an evaporator, a pipe projecting from said gas conduit with a valve casing, said casing containing a spring-pressed valve and a second pipe connecting said valve casing with water in a receptacle surrounding the evaporator.

6. A refrigerating apparatus comprising a generator in which a refrigerant can be converted into a gaseous refrigerant by the application of heat, an upwardly extending gas conduit of straight tubular formation, a closed casing surmounting the gas conduit of which the bottom separates the casing and conduit, a series of annularly disposed openings in said bottom, valves normally closing said openings, a centrally disposed opening in said bottom of the casing, a pipe connecting said opening with the in-

terior of the generator and extending there-
in to a point which is nearly at the bottom
thereof, a pipe connecting said closed cas-
ing with an evaporator, a pipe projecting
from said gas conduit and fitted with a valve
casing, containing a spring-pressed valve,
and a second pipe connecting said valve cas-
ing with water in a receptacle surrounding
the evaporator tubes extending from and
connecting the bottom of the generator with
the wall thereof, and a thermostat in said
generator.

PAUL VUILLAUME.
